UNITED STATES PATENT OFFICE.

HARRY W. DENNY, OF INDIANAPOLIS, INDIANA.

JAR-HOLDING DEVICE.

No. 908,450.

Specification of Letters Patent.

Patented Jan. 5, 1909.

Application filed July 13, 1908. Serial No. 443,304.

To all whom it may concern:

Be it known that I, HARRY W. DENNY, of Indianapolis, county of Marion, and State of Indiana, have invented a certain new and useful Jar-Holding Device; and I do hereby declare that the following is a full, clear, and exact description thereof, reference being had to the accompanying drawings, in which like letters refer to like parts.

The object of this invention is to provide a practical, efficient and satisfactory means for clamping and holding fruit jars and the like while the cap is being placed thereon or removed.

The invention is particularly adapted for use by housewives while canning fruit. When the jar is filled with the fruit at a very high temperature, it is extremely severe, in warm weather during which fruit is usually canned, for the housewife to hold the hot jar from rotation while placing the cap thereon. With the device I have herein shown, she can place the cap on without touching or holding the jar by hand, excepting when the jar is placed in or removed from the holding device herein shown, as the mechanism herein provided will hold the jar, and clamping means for holding and turning the cap is in common use. Therefore, this improvement relieves the canning of fruit of much of its unpleasantness. Furthermore, it removes the danger of the jar breaking in the hands of the person placing the cap thereon and cutting and injuring the hands. Also the cap can be placed more tightly when the jar is firmly held by mechanism.

The chief feature of the invention, whereby the desired result is accomplished, is in providing the apparatus with a flexible metallic band or the like adapted to extend around the jar a plurality of times, one end of said band being held substantially stationary, and a lever or other means connected with the other end and adapted to draw and tighten the band. The said band, therefore, bears on a considerable surface and at many points of the fruit jar so as to distribute the clamping pressure and automatically adjusting the pressure to any irregularities in the circumferential surface, whereby the jar will not be crushed or broken and the jar will be held absolutely from rotation. Along with the foregoing there is provided a spring or yielding connection between said clamping band and the lever for tightening it which greatly promotes the holding power of the band, and

reduces to a minimum the liability of breaking the jar.

Another feature of the invention, contributing toward the successful holding of the jar, is in providing the jar with two stationary bearings or plates provided with holes in which the jar is placed that are spaced apart, and the clamping band is located between said holding plates so that the band will clamp the jar without displacing the same and the bearings between the jar and stationary holding plates will be distributed to avoid breakage.

The full nature of this invention will be understood from the accompanying drawings and the following description and claims:

In the drawings Figure 1 is a side elevation of the device clamped to a table, parts being broken away and parts shown by dotted lines. Fig. 2 is a central vertical longitudinal section thereof. Fig. 3 is a section on the line 3—3 of Fig. 2 showing the clamping device not actuated. Fig. 4 is the same showing the clamping device actuated. Fig. 5 is a perspective view of a clamping band with two coils.

In detail the principle of my invention is herein illustrated by a frame preferably formed of wood, having a bottom plate 10 that is removably clamped to a table 11 by the clamps 12. There are end plates 13 to said frame, a top plate 14 and side bars 15 that are separated to leave a space or longitudinal slot for the operation of the actuating lever 16, whereby the device is operated. The top 14 is provided with a round hole 20 in which the jar is placed and the bottom plate 10 is provided with a similar hole 21, see Figs. 1 and 2.

The lever 16 is fulcrumed at its rear end to the bracket 17 secured to the device and so as to act horizontally. The clamping strap 25 at one end is secured to the pin 26 extending downwardly from a lever 16 near its fulcrum and, therefore, so as to be almost stationary. The clamping band is coiled twice and the other end thereof is fastened to the free end of the spring rod 27 that is held by the bracket 28 on the lever 16. Said band is made sufficiently resilient to maintain its form and the coil thereof when it is relaxed remains expanded within the cylindrical casing 30 that is secured to the bottom plate and extends to the top plate, and is concentric with the vertical center of the opening in the top but is some-

what larger than the diameter of said opening so that it will hold a coil of the band 25, when expanded, in a position that will enable the jar to be readily inserted in place within 5 said coil. The cylinder 30 has two slots 35 through which the ends of band 25 extend.

On the side of the frame a ratchet bar 32 is secured adapted to be engaged by the 10 spring pawl 33 on the outer end of the handle 10 to hold the handle in its actuated position, as shown in Fig. 4.

In operation the device is clamped on a 15 table or any other convenient object and a fruit jar before it is filled is put in place, as shown in Figs. 1 and 2, and then filled. Then the lever 16 is actuated from the position shown in Fig. 3 to that shown in Fig. 4, which causes the band 25 to draw tightly 20 around the fruit jar and clamp it so as to hold it from rotation. Then the cap is secured in place, said band released and the jar removed. The jar can also be held for releasing the cap if desired by inverting the device on the table.

25 The clamping band releases or unwinds within, and is retained in proper place and position by the interior walls of the hollow cylinder 30, the diameter of which is slightly greater than the holes 20 and 21 in the holding or guide plates.

The device has a capacity, within the 30 diametrical limits of the guide holes in the top and bottom plates, of firmly gripping objects of a widely varying range of diameters.

35 What I claim as my invention and desire to secure by Letters Patent is:

1. Means for holding glass jars and the like from rotation which includes a frame 40 with a pair of plates spaced from each other that surround the jar that afford bearings therefor, a band adapted to surround the jar when in place that is located between said plates and is secured substantially station- 45 ary at one end, and means for drawing the

other end so as to tighten the coil of the band about the jar.

2. Means for holding glass jars and the like from rotation which includes a frame for receiving the jar, a resilient band adapted 50 to surround the jar which is secured substantially stationary at one end, and a yielding means for drawing the other end so as to tighten the coil of the band about the jar.

3. Means for holding glass jars and the 55 like from rotation which includes a frame for receiving the jar, a band adapted to surround the jar which is secured substantially stationary at one end, a lever fulcrumed to said frame, and yielding means on said lever 60 to which the relatively movable end of the band is secured.

4. Means for holding glass jars and the like from rotation which includes a cylinder 65 adapted to receive the jar, a resilient band projecting out of the cylinder, and means outside the cylinder for tightening the coil of the band to grip the jar, whereby when the band is released the coil will expand 70 against the cylinder.

5. Means for holding glass jars and the like from rotation which includes a frame having holes in the top and bottom plates thereof for receiving the jar, a cylinder 75 secured between said plates in line with said holes and of greater diameter than said holes, a resilient band coiled within said cylinder with the ends thereof projecting out of the cylinder, means for securing one end of the band substantially stationary, and means for drawing the other end thereof for tightening the coil.

In witness whereof, I have hereunto affixed my signature in the presence of the wit- 80 nesses herein named.

HARRY W. DENNY.
